UNITED STATES PATENT OFFICE.

GEORGE W. WALLERICH, OF CHICAGO, ILLINOIS.

HEAT-THERAPY METHOD AND MEANS.

Application filed February 5, 1925. Serial No. 6,965.

This invention relates to thermatology and to diathermic and electrotherapeutic appliances adapted for local internal treatments and more particularly to such devices 5 adapted for supplying any specific degree of heat or current or both desired to an inner portion of the body, and particularly to an internal organ.

The main objects of the invention are to 10 provide an improved form of apparatus or appliance adapted for the ready supply and control of heat to a limited internal area or portion of the body; to provide such a device, in a form most convenient for application to a point not generally convenient of access where treatment is desired; to provide for effective diathermic and electrolytic treatment of such parts or organs; to provide for most effective and accurate gaging of 20 the resultant temperatures by thermometric means readily observable at all times by an attendant; to provide an intimate contact with the active electrode a thermometer so arranged as to minimize heat insulation of 25 the thermometer relative to said electrode; to provide a device of the character stated in the most compact, unitary and sanitary form possible consistent with mechanical strength and durability.

30 An illustrative embodiment of this invention is shown by the accompanying drawings, in which—

Fig. 1 shows a side elevation of an instrument connected to electrical conductors.

35 Fig. 2 is a side view of the instrument.

Fig. 3 is mainly a longitudinal axial section through the instrument.

Fig. 4 is an end view of the instrument as viewed from the left of Fig. 3.

40 Fig. 5 is a cross section on the line 5—5 of Fig. 3.

In the construction shown in the drawings, the device comprises mainly a tubular glass rod 1 in the form of a thermometer, having 45 an electrically deposited shell 2 on the active end 1' thereof and extending back over the medial body part, and a connector terminal member 3 at the outer end of said shell adjacent to the gage or non-sensitive end of 50 the thermometer where the scale 4 appears, in combination with a detachable tubular casing 5 of insulating material extending from said terminal toward the active tip of the casing, but leaving the tip 2' of said shell 55 or electrode exposed for contact with the body tissues or organ to be treated.

The said terminal member 3 is formed to accommodate ready attachment of an electric wire, for which purpose it is provided with a hole 6 to receive the wire 7 and a set-screw 60 8 for locking the wire in place. Said terminal 3 is also formed with an interiorly threaded cup shaped part 9 concentric with the thermometer receiving hole 10.

The method of making the device is to 65 apply an electro-deposit coating, preferably of copper, to the sensitive end and body part of the thermometer by means well understood by those skilled in the art. The terminal part 3 is then applied and secured permanently to the electro-deposit shell with solder or equivalent means. The protective insulating tube or outer shell 5 is then readily attached by slipping on over the plated end of the thermometer and screwing its terminal 70 engaging end into place in the threaded cup part 9 of said terminal, whereupon the device is ready for use.

In using the instrument, as for instance 80 in the treatment of endocervicitis, the device is applied, by inserting it into the affected organ. A pair of conductors 7 and 7' leading to a source of suitable electric current, are then connected, one to the instrument terminal 3 and the other to an electrode 11 85 placed against the outside of the body at some point adjacent to the part to be treated. Current control means not here shown may be interposed in the circuit 7—7', as will be understood without further explanation. 90

The outside electrode may well comprise a metal plate 11, to which the wire 7' may be attached and this plate should be provided with a layer of fibrous material 12 interposed between the plate and the surface of 95 the body, said material being saturated with a suitable conducting liquid, as for instance a lather of soap and water. The electrode or copper plating 2 is very thin so that the small amount of current used, usually 800 to 100 1,000 milliamperes of a high frequency current, will maintain the desired degree of heat, 116° to 118°, at the tip 2'. The moistened pad 12 distributes the contact of the electrode 11 over a large surface, so that the exterior electrode 11 becomes inactive or indifferent, while the electrode 2 becomes the active electrode. The body of the active electrode extends through a mass of packing material 14 which bears against the insulating shell 5. The tip of the electrode 2 projects into the organ being treated, where the 105 110

heat is maintained at any desired intensity for whatever period is necessary to effect the result sought after. By the arrangement described, a desired degree of heat may be locally applied to the interior of the body, and also the electrical current is caused to flow through the tissues of the body to the external electrode.

Although but one specific embodiment of this invention is herein shown and described, it is to be understood that numerous details of the construction shown may be altered or omitted without departing from the spirit of this invention as defined by the following claims.

I claim:

1. In an electro-therapeutic device, a glass tube thermometer, an electrode comprising a

thin coating of copper formed on the surface of the sensitive end of the glass thermometer tube, and an insulating tube covering the thermometer and electrode with tip of said end exposed.

2. In an electro-therapeutic device, a glass tube thermometer, an electrode comprising a thin coating of copper formed on the surface of the sensitive end of the glass thermometer tube, an insulating tube around the thermometer leaving the lower tip of the electrode exposed, and means for connecting one lead from an electrical source to the electrode coating.

Signed at Chicago this 2nd day of Feb., 1925.

GEORGE W. WALLERICH.
